COLLAPSIBLE TAMPERPROOF BOX AND
TRAY, PRIMARILY FOR CIGARS

Frederick A. Sunderhauf, Rutherford, N. J., and
Frank W. Broderick, New Brighton, N. Y., as-
signors to Reynolds Metals Company, Rich-
mond, Va., a corporation of Delaware

Application September 9, 1939, Serial No. 294,100

1 Claim. (Cl. 229—16)

This invention relates to a new and improved collapsible tamper-proof shipping container, primarily for cigars, which container will normally include a flat-collapsible tray member and a flat-collapsible outer covering member or carton member, the two being adapted for union in an assembly which is tamper-proof.

Heretofore, there have been various attempts to form paper, or cardboard lamination, or metallic foil and paper or cardboard, flat-collapsible shipping containers for cigars, or the like. However, the Governmental authorities have insisted upon rigid specifications for such containers, and to date it is believed that no collapsible cardboard or paper container of the machine made type suitable for large quantities of cigars, with the exception of the collapsible shipping container about to be described, has complied with all Treasury Department regulations and has received the approval of the Governmental authorities. One vital requirement for a container for cigars or the like, is that when the revenue tax stamp is affixed to the container, that it be absolutely impossible for the container to be opened without destroying the revenue stamp, or, alternatively, without mutilating the package.

Therefore, it is the object of our invention to fabricate a paper or cardboard shipping container for cigars or the like, which is capable of being manufactured in large quantities at economical cost and which can be shipped flat to the cigar manufacturer from the paper or cardboard box manufacturer. It will be recognized that the wooden boxes heretofore utilized almost universally for shipping large quantities of cigars in the cigar trade cannot be shipped collapsed.

Therefore, it is a further object of our invention, to provide a sturdy shipping container, primarily for cigars, which includes an inner tray member and a cooperating outer carton member, both members adapted to be collapsed flat for shipping purposes to the cigar manufacturer and both members adapted to be assembled together in upright position to form a stable shipping container for cigars, which will amply protect large numbers of cigars for transportation, and which yet affords an attractive display of the cigars for retail trade purposes.

It is a further object of our invention to provide a flat shipping container, primarily for cigars, which includes an inner tray member and an outer carton member having interlocking means, which permit a single revenue tax stamp

to be affixed to the outer container, sealing the container so that the same is tamper-proof, and so that the said container can not be opened without destroying the revenue stamp, or mutilating the container. The locking means preferably is an integral part of one of the members.

It is a further object of our invention to provide a simple one-piece blank for formulating the outer carton, also a simple one-piece blank 10 for the inner member and also a member so shaped as to provide locking means for the two, thus making it economical for general use.

The above and various other objects and advantages will be readily understood from the 15 following description taken in connection with the accompanying drawings of preferred embodiments of the invention in which modifications may be made without departing from the scope of the appended claim. In the drawings:

Fig. 1 is a plan view of a blank suitable for forming the outer carton member;

Fig. 2 is a plan view of a blank suitable for forming the inner tray member;

Fig. 3 is a perspective view of the assembled 25 tray member, showing the same partially filled with cigars;

Fig. 4 is a perspective view of the assembled outer carton member;

Fig. 5 is a perspective view of an assembled 30 outer carton member with an assembled and a loaded inner tray member partially inserted therein;

Fig. 6 is a perspective view similar to Fig. 5, except that the tray member has been inserted 35 within the carton member, and a locking flap upon the tray member is shown in cooperating position with the outer carton member;

Fig. 7 is a perspective view of the combination 40 shown in Fig. 6, except that the shipping container has been closed and a revenue tax stamp is indicated in position;

Fig. 8 is a cross-section taken upon the line 45 8—8 of Fig. 7;

Fig. 9 is a cross-section of Fig. 7 taken upon the line 9—9 thereof;

Fig. 10 indicates a series of outer carton members, collapsed for shipping purposes;

Fig. 11 indicates a series of inner tray members, collapsed for shipping purposes; and

Fig. 12 is an enlarged cross-section taken upon the line 12—12 of Fig. 6 to illustrate that the outer carton member may be formed of light cardboard stock covered with metal foil, preferably aluminum foil. (It will be recognized that the metal foil increases the moisture-proof and

air-proof characteristics of the shipping container, and also that the metal foil may be embossed and printed upon in attractive designs, but that the shipping container may otherwise be formed of varying thicknesses of cardboard or the like, either with or without metal foil mounted thereupon); and

Fig. 13 is a cross-section of an alternate form of our invention.

In these figures, the outer carton member 10 may be formed of a conventional box-like portion 12 having an opening 14 therein, for the inspection of merchandise, and forming protective corner portions indicated as 16, and a hinged top portion 18. Hinged top portion will preferably have integrally connected thereto side flap portion 20, which in turn has integrally connected thereto, locking tab 22. Flap end portions 24 of conventional design will be provided for box-like member 12. This forms a strong and suitable outer carton member, having a locking means for the cover thereof. As indicated in the plan view of the blank, as shown in Fig. 1, all of the above-identified portions will be formed from a one-piece blank, thereby permitting all of said portions to be joined, one to another.

However, it will be observed that the locking tab 22 in no way affects end portions 24 of outer carton member 10.

It will also be observed that, with the exception of said end portions 24, the outer carton member may be sealed by affixing a revenue tax stamp 25, or like seal, when the locking tab 22 is positioned in locking slot 26, jointly upon side wall 20 and the bottom of the box indicated as 28, all as shown clearly in Figs. 6 and 7.

Therefore, to prevent illicit entry to the contents of the shipping container, we have devised an inner tray member 30 of conventional design, except that it is additionally provided with a locking flap 32 so formed and positioned that the same cooperates with, and fills one side of, opening 14 of outer carton member 10, so that when the tray 30 is in position within the outer carton 10, and locking flap 32 bent outwardly over side portion 34 of carton member 10 (Fig. 6), and the top of the outer carton closed, and this locking tab 22 positioned in locking slot 26, and the revenue tax stamp or seal 25 affixed thereon, the contents of the tray cannot be reached without breaking seal 25, or, alternatively, mutilating end portions 36 of tray member 30.

Tray member 30, as indicated in Figs. 2 and 11, will be formed of conventional design, and

provided with lines of fold 38, except that it will also be provided with locking flap 32, as described. This permits the tray members to be collapsed flat and shipped in a stock, as indicated in Fig. 11, and also readily assembled for loading with cigars, or other merchandise. Also, as indicated in Fig. 10, the outer carton members may also be shipped flat. Fig. 12 illustrates two outer layers of preferably aluminum foil mounted upon an inner layer of paper.

Fig. 13 is a cross section of a modification of our invention wherein the tray 30, instead of being provided with a locking flap 32, is provided with an elongated slot 39 approximately registering and conforming in shape with slot 26, and conforming generally in size and shape to the outer portion of locking tab 22, upon hinged top portion 18. Such a disposition of parts prevents the lateral movement of the tray member when the shipping container is closed and locking tab 22 is inserted through slot 26 and through slot 39.

It will readily be recognized that while our invention is specifically adapted for the shipping of cigars, as described, that owing to the tamper-proof qualities of this shipping container, it is capable of wide utilization for the shipping of other merchandise, particularly because the combination of the two units, namely, the outer carton member and the interlocking inner tray member afford a strong and suitable shipping container.

Therefore, it will be obvious to those skilled in the art that various changes and modifications of the invention may be employed, but it is understood that our invention is not to be limited to what is described in the specification and shown in the drawings, but only as indicated in the appended claim.

40 We claim:

In a tamper-proof shipping container, comprising an open tray member and a collapsible outer carton comprising bottom, side walls and top member, a new sealing means therefor comprising an extension on said tray to overlie one wall of said outer carton, an extension integral with the top of said outer carton to overlie said first extension member and to hold it from being raised, said top extension adapted to be locked in position by a single seal, thereby providing a lock to prevent removal of said tray without the breaking of said extension member or said seal.
